CLAIM

The ornamental design for a lantern as shown and described.

DESCRIPTION

FIG. 1 is an upper perspective view of a lantern showing the new design;

FIG. 2 is a lower perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

The broken lines define the bounds of the claimed design and form no part thereof.
